GEORGE P. BOSWORTH, OF CENTRAL FALLS, RHODE ISLAND, ASSIGNOR TO HEMPHILL MANUFACTURING CO., OF FAWTUCKET, RHODE ISLAND, A CORPORATION OF RHODE ISLAND.

TAKE-UP MECHANISM FOR KNITTING-MACHINES.

1,149,330.

Specification of Letters Patent. Patented Aug. 10, 1915.

Application filed January 4, 1915. Serial No. 473.

To all whom it may concern:

Be it known that I, GEORGE P. BOSWORTH, a citizen of the United States, residing at Central Falls, Rhode Island, have invented 5 certain new and useful Improvements in Take-Up Mechanism for Knitting-Machines, of which the following is a specification.

My invention relates to take-up mechanism for stocking knitting machines having 10 a rotary and reciprocating needle cylinder and one object is to provide a take-up which will perform its take-up action continuously during round knitting and will automatically become inoperative during heel and toe 15 knitting; this being desirable because then the fabric is hanging on one half the needles which are idle, and are not casting off stitches.

The invention consists in the features and 20 combination and arrangement of parts hereinafter described and particularly pointed out in the claims.

In the drawings: Figure 1 is a front view of the take-up mechanism and the revolving can which receives the goods from the needle cylinder, a part of the frame of the machine being shown in this view partly in section. Fig. 2 is a view of the take-up mechanism and receiver or can taken a quarter turn from Fig. 1. Fig. 3 is a detail sectional view. Fig. 4 is a view of gearing connecting the take-up rolls. Fig. 5 is a view of a detail.

In these drawings, the needle cylinder 1 is of the ordinary construction as employed 25 in stocking machines, for instance of the Hemphill or "Banner" type having a gear 2 by which it is driven. 30

3 indicates a part of the fixed frame in 40 which the gear is housed.

Depending from the needle cylinder is a tube 4 of tin or other light material through which the fabric as it leaves the needle passes to a receiver or can 5 after passing 45 through the take-up rolls 6, 6'. These are journaled in the sides of a bracket or connecting member 7 located between the lower end of the tin tube and the can and serving as the connection between these. This 50 bracket has formed therewith a cylindrical portion 8 in which the lower end of the tin tube fits, it being brazed or otherwise secured thereto. This cylindrical portion of the bracket supports loosely a cam or con-

trolling ring 9 by a flange 10 at the upper edge of the cam or controller resting on the upper edge of the cylindrical portion of the bracket as shown in Fig. 3 or in dotted lines, Fig. 1. The cam or controller is formed with an inclined or cam shaped lower edge at 11 to be engaged by a pin 12 of a pawl lever 13 pivoting about a shaft 14 mounted in the sides of the bracket 7. This pawl lever has pivoted thereto a pawl 15 under tension of a spring 16 which keeps the pawl in engagement with a ratchet wheel 17 fixed on the shaft 14. The shaft 14 carries a gear 19 meshing with a gear 20 on the shaft of the take-up roller 6 and gear 19 meshes also with a gear 21 journaled on a pin 22 carried by one side of the bracket 7, and this gear meshes with the gear 22 on the shaft of the other take-up roll 6'. The shaft of the take-up roller 6 is journaled in slots 23 formed in the sides of the bracket 7 so that the said roller 6 may have movement to and from the other take-up roll 6'. The take-up roll 6 is held yieldingly against the roll 6' by springs 24, connected with the axes of the said gears. This yielding mounting is to permit the passage of thickened portions of the fabric or bunches of lint or raveling. During round knitting the cam or controller 9 is held against rotation by engaging a suitable fixed member. 85 This may be provided for in various ways but in the particular construction shown, the cam ring has a stop projection 25 fixed thereon which engages a stop projection 26 fixed on a suitable part of the stationary frame of the machine as for instance, the flange 27. The tin tube is fixed to the needle cylinder or rather to the gear 2 thereof by the screws 28 passing through ears or lugs 29 of a ring 30 brazed or otherwise 95 fixed on the tin tube. This connection imparts to the tin tube and to the can either the continuous rotary motion of the needle cylinder, while doing round knitting, or the rotary reciprocating movement, during the 100 formation of the heel or toe pockets. The can, take-up and tube are sustained by a pin or bearing member 31 adjustably mounted in a fixed bracket 32, secured to the stationary frame of the machine, indicated 105 generally at 3, before mentioned. This pin or bearing takes the weight of the can, take-up and tube while the screws 28 impart the

motion of the needle cylinder to said parts. By lowering the bearing 31 the tin tube with the take-up can be dropped down off from the screws 28 for the removal of said parts from the machine.

In operation and while the machine is on round knitting, the rotation being in the direction of the arrow *a* the tin tube, take-up and can will revolve in said direction, 10 while the loosely mounted cam or controller will remain stationary because its stop projection 25 will be bearing against the fixed frame projection or stop 26. As the pawl lever travels around its pin 12 will ride on the inclined or cam shaped lower edge of the controller, which is now stationary and consequently, being under tension of the spring 16', the pawl lever will be rocked up and down and its pawl will therefore 15 turn the ratchet 17 one step for each revolution of the can and tin tube and the take-up rollers being driven from this ratchet through the gearing described, the taking up of the fabric will be performed and the 20 fabric after passing between the take-up rollers will be stored in the can 5 which also is in rotation. Backward movement of the ratchet will be prevented by the detent 32', Fig. 1, pivotally mounted on one side of 25 the bracket 7 and pressed by a spring 33. Now when the machine goes on reciprocating knitting for the formation of the heel and toe pockets, the tin tube together with the can and take-up will reciprocate also, 30 being connected as before stated, with the needle cylinder driving gear. At this time it is desirable that no take-up action of the 35 rolls 6, 6' be performed because at this time, the knitted fabric is hanging on the inoperative needles and no stitches are being added 40 to the main portion of the tubular fabric. In other words, regular knitting has ceased and the formation of the heel and toe is being done. As soon as the rotary reciprocating motion begins, the cam or controller 45 9 will partake of this motion owing to the frictional contact between the said cam or controller and the part or ring 8 upon which it bears and therefore the relative position 50 of the cam to the pin 12 will be maintained all the parts reciprocating together. Consequently no motion will be transmitted to the pawl lever and the take-up rolls will remain 55 idle as no take up action will be accomplished. This condition obtains until the heel or toe pocket has been completed and round knitting is resumed whereupon the cam or controller will be arrested by the stops 25 and 26 and then the pawl lever will 60 be oscillated by the combined action of the pin 12 riding against the edge of the cam and the retractable spring 16.

It will be observed that the cam edge extends practically throughout the entire circumference of the cam or controller, that is, the in-

clined edge extends substantially continuously from the high to the low part of the cam, giving a gradual movement to the pawl lever and avoiding the noise and shock that results where a tappet on the take up strikes a tappet on the frame. All tappet action is avoided by my construction, and this result flows from the fact that during reciprocating knitting the relation of the cam to the pawl carrying lever with its pin 12 is not altered and hence a long incline can be employed, this being substantially the full circuit of the cam edge.

In cases where the needle cylinder or reciprocating member makes a full revolution or more the loose cam ring will still perform the function above mentioned, of preventing the operation of the take-up during reciprocating knitting as the slight motion of the cam in relation to the take-up, due to the stops 25 and 26 coming in contact will not be sufficient to operate the pawl lever, the pin 12 of which is held normally off from the cam edge a slight distance by the pawl lever bearing against the stop 35 which is adjustably held by the screw 36.

I claim as my invention:

1. A take-up mechanism having connection with the knitting head to revolve continuously or reciprocate therewith and in combination, take-up rolls, a cam or controller, means for holding said controller against revolution with the take-up during round knitting, and means for operating the take-up rolls from the controller, said controller being free to reciprocate with the take-up during heel and toe knitting, substantially as described.

2. A take-up mechanism for stocking knitting machines, comprising take-up rolls, a mounting therefor, connected with the knitting head to revolve therewith bodily in one direction or to reciprocate therewith, a cam ring or controller revoluble with said mounting, means for holding the said ring against revolution during round knitting and permitting the same to revolve with the said mounting during reciprocating knitting, and means for operating the take-up rolls from the cam ring while the same is stationary, substantially as described.

3. A take-up mechanism for stocking knitting machines, comprising take-up rolls, a mounting therefor revolving bodily with the knitting head, both during round knitting and reciprocating knitting, a cam ring carried by said mounting to revolve therewith except when restrained, stop means on the fixed frame to contact with a portion of the cam ring to hold the same against rotation during round knitting but permitting said ring to revolve with the take-up mounting during reciprocating knitting, and means carried by and revolving with the mounting and operated from the cam when sta-

tionary for rotating the take-up rollers step by step, substantially as described.

4. In combination in a take-up for stocking knitting machines, take-up rolls, a mounting therefor with means for connecting the same with the rotary part of the knitting head, a cam ring arranged coaxially with said mounting and carried frictionally thereby to revolve at times therewith, stop means on the frame for holding the cam against revolution during round knitting, said stop means permitting the cam ring to revolve with the take-up during reciprocating knitting and means revolving with the mounting and operated by the cam when held stationary for rotating the take-up rolls step by step, substantially as described.

5. In combination in a take-up for stocking knitting machines, take-up rolls, a mounting therefor with means for connecting the same with the rotary part of the knitting head, a cam ring arranged coaxially with said mounting and carried frictionally thereby to revolve at time therewith, stop means on the frame for holding the cam against revolution during round knitting, said stop means permitting the cam ring to revolve with the take-up during reciprocating knitting and means revolving with the mounting and operated by the same when held stationary for rotating the take-up rolls step by step, said means comprising a spring pressed pawl carrier bearing on the cam edge, a pawl on said carrier, and a ratchet connected with the take-up rolls, substantially as described.

6. In combination, the take-up rolls, a mounting therefor having means of connection with the knitting head to revolve therewith during round knitting or to reciprocate during heel and toe work, a cam encircling the axis of said mounting and frictionally carried by the mounting to revolve therewith at times, a spring pressed pawl lever carried on the mounting to revolve therewith and operated by the cam edge, a pawl on said lever, a ratchet operated by the pawl and connected with the take-up rolls, and stop means for holding the cam ring against revolution with the take-up mounting during round knitting, substantially as described.

7. In combination, the take-up rolls, a mounting therefor having means of connection with the revolving member of the knit-

ting head, a cam encircling the axis of said mounting and frictionally engaging said mounting to revolve therewith during reciprocating knitting, fixed stop means for holding said cam against revolving with the mounting during round knitting and means revolving with the mounting and operated by contact with the cam for rotating the take-up rolls, step by step during round knitting, said cam having a cam edge substantially continuously inclined from its high to its low point, substantially as described.

8. In combination in a take-up mechanism for stocking machines, a tube to receive the fabric from the knitting head, said tube having means of connection with the knitting head to revolve continuously in one direction, or reciprocate therewith, a cam ring loosely hung on said tube and having its lower edge inclined, said cam revolving with said tube during reciprocating knitting by its frictional contact with the tube, stop means on the fixed frame for holding said cam against revolution during round knitting, take-up rolls bodily revolving with the tube, means also bodily revolving with the tube and engaging the cam to be operated thereby when the latter is held against revolution, said means operating the take-up rolls, step by step, substantially as described.

9. In combination the take-up rolls, a mounting therefor having means of connection with the revolving member of the knitting head, a cam encircling the axis of said mounting, and frictionally engaging said mounting to revolve therewith during reciprocating knitting, fixed stop means for holding said cam against revolving with the mounting during round knitting, and means revolving with the mounting and operated by contact with the cam for rotating the take-up rolls step by step during round knitting, said cam having a high point on one side thereof and a low point at substantially the opposite side thereof with inclined edges between substantially continuous from the high to the low point, substantially as described.

In testimony whereof I affix my signature in presence of two witnesses.

GEORGE P. BOSWORTH.
